METHOD AND APPARATUS FOR THREADING
HOLLOW METAL ARTICLES

Herman A. Unke, Cleveland, Ohio

Application February 18, 1935, Serial No. 7,060

12 Claims.

(Cl. 80—6)

This invention relates to a novel method and apparatus for rapidly and economically forming threads on the walls of hollow metal articles.

An object of the present invention is to provide 5 a novel method for threading hollow metal articles comprising the displacing of metal of the wall of the article radially by pressure applied on one side thereof, and in the same operation forming at least a portion of the displaced metal 10 into a continuous solid thread on the other side of the wall.

Another object of the invention is to provide a novel method of threading relatively thick walled 15 hollow metal articles which comprises displacing metal of the wall of the article radially by applying pressure on one side thereof and shaping the displaced metal into a continuous solid helical thread on the other side of the wall, and meanwhile supporting the metal of the wall at each 20 side of and immediately adjacent to the metal being displaced.

Still another object of the invention is to provide a novel method of forming a solid continuous 25 helical thread on a tubular metal article, which comprises shearing and displacing metal of the wall of the article radially thereof, and in the same operation shaping at least a portion of the displaced metal into a solid continuous thread.

It is also an object of this invention to provide 30 improved thread forming apparatus for carrying out the novel method of my invention.

Another object of the invention is to provide improved thread forming apparatus, of the type referred to, embodying dies of novel construction 35 and also embodying novel means for supporting and actuating the dies.

Yet another object of this invention is to provide a novel method and apparatus for removing the threaded articles from the dies.

40 Other objects and advantages of this invention will be apparent from the following description when taken in conjunction with the accompanying sheets of drawings, wherein

Fig. 1 is a longitudinal sectional view taken 45 through improved thread forming apparatus constructed according to my invention.

Fig. 2 is a transverse sectional view taken through the die members, as indicated by line 2—2 of Fig. 1.

50 Fig. 3 is a transverse sectional view taken as indicated by line 3—3 of Fig. 1.

Fig. 4 is a transverse sectional view taken through the driving gearing, as indicated by line 4—4 of Fig. 1.

55 Fig. 5 is a sectional view illustrating a detail of construction and taken on line 5—5 of Fig. 1.

Fig. 6 is an elevational view with parts broken away, showing the cooperating die members and illustrating the thread forming action thereof.

60 Fig. 7 is a partial sectional view, on an enlarged

scale, showing the forming of the thread by the die members in accordance with my novel method.

Fig. 8 is a side elevation of a threaded article produced by my novel method and apparatus. 5

Fig. 9 is an end view thereof, and

Fig. 10 is a partial sectional view, on an enlarged scale, with the article applied to a threaded member and showing the cooperation between the threads of the article and of the member to 10 which it is applied.

In the accompanying drawings to which more detailed reference will now be made, I have illustrated the manner of carrying out my novel thread forming method, and have illustrated one 15 form of threaded article which may be produced thereby. I have also illustrated one form of novel apparatus which may be used for applying my novel method to the commercial production of threaded tubular metal articles. It will be understood, of course, that various kinds of threaded 20 articles may be produced by my method, and that that feature of my invention which has to do with the adaptation of my method to the commercial production of threaded articles, may be 25 embodied in various kinds of apparatus and machinery.

Before proceeding with a detailed description of my novel thread forming method and apparatus, I shall describe briefly one form of tubular 30 metal article which can be readily produced by the use of that method and apparatus. The article illustrated in this instance is a thread protector intended for use on the ends of pipes, or other threaded members, and is more fully disclosed in copending application, Serial No. 717, 35 635, filed March 27, 1934. It will be understood, of course, that the specific form of threaded article here referred to, is merely in illustration of the method and apparatus of my invention, and that the invention may be applied to the production of numerous other threaded metal articles.

As shown in Figs. 8, 9, and 10 of the drawings, 45 the thread protector 15 referred to in this instance, comprises a relatively thick walled metal sleeve, such as might be formed by suitably drawing or shaping a sheet metal blank in appropriate dies. The metal sleeve is provided on one side 50 thereof, in this instance on the inside, with a continuous solid helical thread 16, which is formed, at least in part, from metal displaced substantially radially inwardly of the wall of the sleeve. Such displacement of metal to form the solid 55 thread leaves a helical groove 17 in the outer surface of the sleeve. The helical thread 16 is of V-like form, as shown in Fig. 10, and engages in adjacent convolutions of the thread groove 18 of a pipe end 19 or other threaded member to 60

which the article is applied. The helical thread 16 may comprise any desired number of convolutions, and in this instance, forms a threaded section intermediate the ends of the tubular metal 5 article.

One end of the threaded article 15 is open so that the article may be readily applied to the end of a pipe or other member and screwed onto the threads thereof. The opposite end of the article 10 has an integral inwardly extending flange 20 which is adapted to engage the end portion of the pipe or threaded member with a locking action, so as to retain the threaded article against unscrewing or becoming jarred loose from the 15 end of the member to which it is applied. The inwardly extending flange 20 may be shaped to an out-of-round condition, as shown in Fig. 9, so as to improve the locking action just explained. This out-of-round condition of the flange 20 may 20 also be utilized in connection with a novel method and apparatus for removing the threaded articles from the dies, as will be explained more fully hereinafter.

As mentioned above, my novel method contemplates forming a solid continuous helical thread on one side of the wall of a tubular metal article, by displacing metal radially of the wall and shaping at least a portion of such displaced metal to form the solid helical thread. My novel method 25 also contemplates the supporting of the metal of the wall at spaced points and the application of pressure to the opposite side of the wall at points intermediate the points of support, whereby by the metal of the wall is subjected to a shearing action which displaces metal substantially radially to form the continuous solid helical 30 thread.

I am aware that it has been proposed heretofore to form threads on tubular metal articles 40 by cooperating die members, but in all cases of which I am now aware the forming of the threads was accomplished by a deflecting or bending of the metal of the wall of the article. Threads can be formed in this manner on relatively thin 45 walled articles, but the threads are not solid threads nor are they of a desired V-like shape. Furthermore, attempts to form such threads on relatively thicker walled articles by a deflecting or bending of the metal has resulted in threads 50 of unsatisfactory character and has resulted in excessive strains and wear on the thread forming dies.

In accordance with my novel method, metal of 55 the wall of the tubular article is actually sheared and displaced transversely of the wall, and at least a portion of the displaced metal is shaped into a solid, continuous helical thread. The thread thus formed is of a desired V-shape, and is also very strong and rugged as compared with 60 the hollow threads formed by deflecting or bending of the metal as heretofore proposed.

Dies of various forms may be used in carrying out my novel thread forming method, and in 65 the drawings I have shown one form and arrangement of dies satisfactory for this purpose. These dies, as illustrated in this instance, may comprise an anvil roll or mandrel 25 having a continuous helical groove 26 formed therein, and 70 one or more die rolls 27 which are the same diameter as the mandrel and are disposed adjacent thereto. The rolls have on their outer surface a ridge or ridges in opposed relation to the helical groove 26.

75 The ridge or ridges of the die rolls 27 are pref-

erably arranged to form a helical thread 28 which is of opposite hand to the helical thread of the mandrel. As shown in Figs. 6 and 7 the consecutive convolutions of the thread 28 of each roll lie opposite the consecutive convolutions of the 5 thread groove of the mandrel, and where the article 15 is to have an internal right hand thread the mandrel is provided with a right hand thread groove and the roll 27 is provided with a left hand thread ridge 28. In this instance, I have shown three die rolls 27, spaced at equal intervals circumferentially around the mandrel 25, but any desired number of such rolls may be employed.

As best shown in Fig. 7 of the drawings, the helical groove 26 of the mandrel 25 has tapered 10 side walls 29 which converge to provide the groove with a V-like bottom. Outwardly of the convergently tapered wall 29, the groove 26 has substantially parallel side faces or walls 30. The groove 26 is formed in the surface of the mandrel so as 15 to leave upstanding spiral ridges or lands 31 between adjacent convolutions of the groove. The tops of these ridges or lands are flat or square, as shown in Fig. 7, and have supporting engagement 20 with the inner surface of the tubular metal article 15 when the latter is applied to the mandrel.

The thread 28 of the die roll 27 has the same 25 pitch as the thread of the mandrel 25, and hence the adjacent convolutions or ridges thereof are spaced apart a distance corresponding with the spacing or pitch of the adjacent convolutions of the groove 26. The convolutions of the thread 30 28 also have flat or square tops of substantial width, similar to the lands or ridges 31 of the mandrel. The ridges of the die roll are preferably somewhat narrower than the width of the groove 26, although the proportions of the ridges and grooves may be varied in accordance with the characteristics of the thread to be formed and also in accordance with the characteristics of 40 the metal to be worked. The purpose of the ridges 28 is to force metal of the article 15 in a direction transversely of the wall thereof and into the convolutions of the helical groove 26. In accomplishing this function the ridges 28 cooperate with 45 the lands 31 in subjecting the metal of the wall to a shearing action, whereby the metal is sheared and displaced at axially spaced points and is forced into the helical groove 26, and at least a portion of the displaced metal is shaped by the 50 mandrel groove into the desired V-like solid continuous thread 16. During this shearing action the flat faces of the lands 31 support the metal of the wall of the article at each side of and immediately adjacent to the metal being displaced by 55 the ridges 28. In Fig. 7 of the drawings I show the lands 31 in such supporting relation with the wall of the metal sleeve, and it will be seen that as the displaced metal is shaped into the V-like 60 thread 16, the square tops of the lands also serve 65 to form the square recess 31' at the bottom of the thread groove. This square recess is desirable in the article 15 because it provides a clearance space for the top edge of the thread to which the article is applied and prevents dulling of the 70 thread.

Although my novel method for threading hollow metal articles may be carried out with various kinds of machinery and apparatus, as mentioned above, I have devised novel apparatus with which 75 this method can be carried out especially well. This apparatus may include a support or frame 75 which may be mounted upon a suitable bed or foundation 80. The frame may have an enlarged portion 85 adjacent which the die members are ar- 75

ranged, and another enlarged portion 38 adjacent which the driving gearing may be arranged. The enlarged portion 37 is provided with substantially radially extending guide-ways 39 which correspond in number and spacing with the number and spacing of die rolls 27 to be employed. Bearing members, preferably in the form of metal blocks 40, are mounted for radial sliding movement in the guide-ways 39, and are normally urged radially outwardly within the guideways by means of springs 41. These springs may be arranged on studs 42 which are carried by the bearing members and extend outwardly through the cover plates 43, the springs being disposed between the heads of the studs and the cover plates.

A spindle 45 is rotatably mounted in each of the bearing blocks 40, with the ends 46 and 47 thereof extending in opposite directions beyond the bearing member. The end 46 of the spindle extends in adjacent relation to the mandrel 25 with its axis substantially parallel to the axis of the mandrel. The oppositely extending end 47 of the spindle projects through a radially elongated slot 48 of the frame portion 31. The projecting portion 46 of the spindle may be provided with a threaded section 49 at its outer end and with successive shaft portions 50 and 51. The shaft portion 50 is of smaller diameter than the portion of the spindle which is journaled in the bearing block 40 to provide a shoulder 52 on the spindle, and similarly the shaft portion 51 is of smaller diameter than the shaft section 50 to provide a second shoulder 53 outwardly of the shoulder 52. The die rolls 27 are mounted upon the projecting ends 46 of the spindles by being keyed to the shaft sections 51 so as to be driven by the spindles. The rolls are retained on their respective spindles by means of bushings 54 which are disposed on the shaft sections 51, so that the bushings and the rolls are clamped between the shoulder 53 and a nut 55 applied to the threaded outer section 49 of the spindles.

The mandrel 25 may be supported for cooperation with the die rolls 27 by a shaft 60, which is suitably journaled in the frame 35 with an end 61 thereof projecting outwardly from the frame member in substantially parallel relation with the spindles 45. The mandrel 25 is keyed, or otherwise connected, to the shaft end 61 so as to be rotated thereby. Provision may be made for axial movement of the mandrel, for a purpose to be presently explained, by arranging the shaft 60 for axial movement in the bearings 62, or preferably by providing a spline connection between the shaft end 61 and the mandrel 25, whereby the mandrel is axially shiftable on the shaft while it is being driven thereby.

When one of the metal articles 15 is to be threaded, the tubular blank for the article is telescoped over the mandrel 25 and the spindles 45 are then moved substantially radially inwardly with respect to the axis of rotation of the shaft 60 to cause the ridges 28 of the die rolls 27 to engage the outside of the metal sleeve and to displace metal from the wall thereof into the helical groove 26 to form the continuous solid thread on the article. During such inward movement of the die rolls 27 the spindles supporting the rolls are maintained in proper relation with respect to the axis of the shaft 60 by the sliding bearing members 40 in which the spindles are mounted.

For moving the spindles toward the shaft 60 to press the die rolls 27 against the metal sleeve, as just explained, various arrangements of apparatus may be employed. I prefer, however, to use

suitable cam means for this purpose, and one cam arrangement is shown in the drawings wherein an annular member 65 is disposed around the die rolls 27 and carries cam members 66 and 67 for causing the desired actuation of the die rolls. The annular member 65 may be supported for rotation by a pair of flanged rollers 67', which are rotatably mounted on the frame. These flanged rollers are disposed in laterally aligned relation, as shown in Fig. 2, and are spaced apart a distance such that the annular member will be directly supported on these rollers and will be confined to the desired path of rotation by the flanges of the rollers.

The cam members 66 and 67 are arranged within the opening of the annular member 65, as shown in Figs. 1 and 2, with the cam members 66 extending in a circumferential series adjacent one end of the annular member and the cam members 67 extending in a circumferential series adjacent the opposite end of the annular member. The cam members 66 and 67 correspond in number with the die rolls 27, and in this instance there are three cam members in each circumferential series. The cam members of each series form a substantially complete ring, the outer surface of which engages the inner face 68 of the annular member 65. The cam members of the two series are in edge to edge engagement with each other, as shown in Fig. 1, and may be retained in the opening of the annular member 65 by being axially clamped between the integral radial flange 69 which is provided at one end of the annular member 65, and the removable clamping plate 70 provided at the other end of this member. The cam members 66 and 67 may be retained against dropping away from the inner face 68 of the annular member 65 by providing a bevel on the adjacent faces of the flanges 69 and 70, and on the edge portions of the cam members engaged by these flanges, as indicated at 70'. Relative rotation between the cam members and the ring member 65 may be prevented by one or more dowel pins 71 which extend through the flanges 69 and 70 and through the cam members.

The adjacent end faces of the cam members 66 and 67 have recesses formed therein and which register to form an annular groove 72 when the die members are assembled in the annular member 65. This annular groove accommodates the outer portion of die rolls 27, while the cam faces of the members 66 and 67 form annular cam surfaces 73 and 74 at each side of the annular groove 72. The cam surface 73 cooperates with an antifriction roller 75, which is rotatably mounted on the bushing 54 of the shaft section 51 of the spindle, and the cam surface 74 cooperates with a similar roller 76 rotatably mounted on the shaft section 50 of the spindle.

As mentioned above, the cam members 66 and 67 are provided in number to correspond with the number of die rolls 27, and in order to have substantially simultaneous actuation of all of the die rolls, these cam members have cam surfaces of substantially identical contour. In Fig. 2 of the drawings the direction of rotation of the annular member 65 is indicated as being clockwise, and the antifriction rollers 75 and 76 of the spindles are shown as being at the starting points of the respective cam members. When the annular member 65 has been rotated through an angular distance to bring the elevated cam portions 71 into engagement with the antifriction rollers, the spindles are shifted inwardly toward 75

the mandrel 25 and the die rolls 27 are pressed against the tubular metal article being threaded.

The elevated cam portions 77 extend through an angular distance such that when the annular member 65 and the mandrel 25 are rotated, the die rolls 27 will travel over different portions of the sleeve of the article 15 and such portions will aggregate at least the full circumference of the sleeve. The cam portions 77 are preferably long enough to cause each of the rolls 27 to overrun to some extent the thread portions formed by the preceding die roll, so that the thread portions formed by each roll will merge with and be a smooth continuation of the thread portions formed by the preceding roll. The elevated cam portions 77 are followed by relatively depressed cam portions 78 which allow the spindles 45 to be moved outwardly with respect to the shaft 60 by the springs 41. Such outward movement of the spindles causes the ridges of the die rolls 27 to be disengaged from the work to permit removal of the latter from the mandrel 25. During the action of the cam members, as just described, the annular member 65 rotates for one-third of a revolution, that is to say 120°, which causes one set of cams 66 and 67 to act on and travel past one of the die rolls 27. During this same period of time, that is while the annular member 65 makes one-third revolution, the mandrel 25 and the die rolls 27 each make two revolutions.

Since the groove 26 of the mandrel 25 is a spiral groove, it is necessary to have the die rolls 27 keyed to their driving spindles 45 so that the ridges 28 of all of the rolls will be opposite the convolutions of the groove 26 of the mandrel. With the ridges and grooves of the rolls and mandrel in this relation, the ridges of the rolls will follow the grooves of the mandrel as the rolls and mandrel are rotated, and in so doing, will form the desired threaded section on the article. In arranging the rolls 27 in proper relation to the thread grooves of the mandrel, it may be desirable to insert shims 19, of proper thickness, between one or more of the rolls and their clamping shoulders 53.

The mandrel 25 may, as mentioned above, be splined to the shaft portion 61 so as to be adjustable thereon, and for adjusting and holding the mandrel in proper relation to the rolls 27 without the need of reaching into the recess of the annular member 65 with tools, I provide the mandrel holding and adjusting bracket 80. This bracket extends into the recess of the annular member 65 and has a fork portion 81 engaging in an annular groove 82 of the mandrel. The bracket 82 may be mounted for sliding movement on a guide rod 83, which is disposed below the shaft 60, with its axis extending substantially parallel to the axis of the shaft.

The bracket 80 may be normally held against movement on the rod 83 by means of a cam or bushing 84 having operative connection with the bracket. The bushing 84 is mounted on a drive shaft 86 and has an annular groove 87 in its outer surface. The shaft 86 may be suitably journaled in the brackets 86' and 87' of the machine frame. The bracket 86 may have an enlarged bearing portion 88 which is journaled on the bushing 84 and which has a roller 89, or the equivalent, arranged to operate in the groove 87. The roller 89 may be mounted on a pin 90, which is screwed into a threaded opening 90' of the bearing portion 88 as shown in Fig. 5, or the roller may be otherwise suitably mounted on the bearing portion.

The groove 87 may be a circular groove which, when the shaft 86 and the bushing 84 are rotated, will act upon the roller 89 to cause the bracket to hold the mandrel 25 in the desired axial position relative to the die rolls 27. If it should be desirable to have relative axial movement between the mandrel and the rolls 27, such as when the latter are narrower than the section to be threaded on the article or when the ridges of the rolls are parallel to each other instead of in the form of a helical thread, the groove 87 may be shaped to cause any desired extent of such axial movement of the mandrel. Usually, however, the groove 87 is a circular groove, as mentioned above and when it is desirable to adjust the mandrel axially with respect to the rolls 27, such adjustment is made by shifting the bushing 84 along the shaft 86. For this purpose I mount the bushing on the shaft 86 between the nuts 84' of the latter. By adjustment of these nuts, the bushing can be adjusted along the shaft 86 and clamped at a point corresponding with a desired adjustment of the mandrel 25.

For driving the die rolls 27 and the mandrel 25, and also, if desired, the shaft 86, in timed relation to cause proper cooperation between the rolls and mandrel to form the threads on the article, I provide a common source of power for driving these various parts. In this instance the power source is represented as being a flanged head 90, which may be the flanged end of a power shaft, the head of a lathe or any other suitably driven power member. The shaft 60 has direct driving connection with the head 90, and in this instance, such direct driving connection is established through a gear 91 which is pinned or otherwise connected to the extension 92 of the shaft 60, and is also connected as by dowel pins 93 or the like with a collar 94 which is, in turn, bolted or otherwise secured to the head 90.

The spindles 45, as mentioned above, are arranged for substantially radial shifting movement relative to the shaft 60 and, as a feature of my invention, I provide flexible driving means for these spindles. In this instance the flexible driving means consists of a flexible shaft 95 for each spindle. This flexible shaft may comprise an extensible intermediate portion 96 and universal joints 97 and 98 which are connected, respectively, to the spindle portion 47 and to a stub shaft 99 or spindle 99 which is journaled in, and extends through, the frame portion 38. The extensible intermediate part of the flexible shaft 95 may be formed by telescoping shaft sections of the universal joints 97 and 98 which shaft sections are drivingly connected by a pin and slot connection 100 or the like. Rotation is imparted to the flexible shafts 95 by pinions 101 which are pinned or otherwise secured to the spindles 99 and which mesh with the gear 91.

To provide a suitable power take-off for driving the annular member 65 and the cam shaft 86 in properly timed relation to each other and to the shafts 60 and 95, I may employ a ring gear 103 which is arranged for movement relative to the driving head 90. This ring gear has internal teeth 104 which mesh with the pinions 101 and external teeth 105 which mesh with the gear 106 of a counter-shaft 107. To permit movement of the ring gear 103, relative to the head 90, I connect the ring gear to a supporting member 108 which is rotatably mounted on the flange of the head and retained thereon by the plate member 109.

The counter-shaft 107 is suitably journaled in

the frame 35 and has a gear 110 secured thereto which meshes with an external ring gear 112 to cause rotation of the annular member 65. The ring gear 112 may be formed on the annular member itself, or, as shown in Fig. 1, may be secured to the annular member by suitable bolts 113.

Rotation may be transmitted to the cam shaft 86 through a gear train consisting of gears 115, 116, 117 and 118, and a counter-shaft 119 upon which the gears 116 and 117 are mounted. The shaft 119 may be suitably journaled in the brackets 86' and 87' below the shaft 86, as shown in Figs. 1 and 3. The gear 115 is an idler, which is journaled on the shaft 86 and transmits motion to the gear 116, the latter being keyed to the shaft 119. The gear 117 is also keyed to the shaft 119 and transmits rotation from this shaft to the gear 118 which is keyed to the shaft 86.

From the driving arrangement just described it will be seen that when the head 90 is rotated it will cause the shaft 60 to be directly driven at a corresponding speed, and will also cause the die rolls 27 to be driven through the gears 101 and the flexible shafts 95. At the same time rotation will be imparted to the ring gear 103 through the gears 101, and from the ring gear 103 rotation will be transmitted through the counter-shaft 107 to the annular member 65 which carries the cam members 66 and 67. From the ring gear 112 of the annular member 65, rotation will also be imparted to the shaft 86 and the cam or bushing 84 thereon.

In the operation of the apparatus the operator places a sleeve-like metal blank on the mandrel 25, and by means of a suitable clutch or other control (not shown), starts rotation of the driving head 90. Rotation is imparted to the mandrel, the die rolls 27, the cam-carrying annular member 65, and the bushing 84 in the manner just explained, which causes the cam rolls 27 to act on the work and cooperate with the mandrel 25 to form the solid continuous thread on the article. When the die members have traveled through the desired relative movement, as explained above, the apparatus is brought to a stop by either manual or automatic operation of the clutch and the threaded article may then be removed from the mandrel.

Since the metal, which is displaced from the wall of the article in forming the thread thereon, is pressed into the helical groove of the mandrel, it will be seen that it is usually necessary to rotate the article relative to the mandrel in order to remove the same. This rotation may be accomplished as a hand operation by the operator, but I prefer to provide power means for this purpose. Such power means is shown in Fig. 1 of the drawings and may comprise an axially movable spindle 125, which is mounted with its axis in substantial alignment with the axis of the shaft 60. A die or gripping device 126 of appropriate construction is provided at the inner end of the spindle for gripping cooperation with the threaded article 15. Such gripping cooperation may be obtained by forming a part of the gripping device so that it will enter the out-of-round opening of the end flange 29 of the threaded article to establish a driving connection between the spindle 125 and the article.

Rotation may be imparted to the spindle 125 by an electric driving motor 127, having a drive shaft 128 connected with a speed reducing device 129 through which the spindle 125 extends.

In the operation of the article removing appa-

ratus, the operator closes a switch in the power circuit of the motor 127 as soon as the threading of the article has been completed. This causes the motor 127 to drive the spindle 125 through the shaft 128 and the speed reducer 129, and results in the spindle 125 being moved toward the shaft 60 to bring the gripping device 126 into engagement with the article, whereupon the spindle 125 rotates the article in a direction to unscrew the same from the mandrel 25. The operator then manipulates the control switch for the motor 127 to reverse the direction of rotation of the motor, thereby causing the spindle 125 to move away from the shaft 60 and to carry the article 15 in the same direction. When the article has been moved through a sufficient distance to clear the annular member 65, the motor circuit is opened and the motor is suddenly brought to a stop by substantially simultaneous operation of a magnetic brake 130. The sudden stopping of the motor and of the spindle 125 by the action of the brake 130, causes the article 15 to be subjected to a sudden jar which shakes the article loose from the gripping device 126. Thereupon the article drops in a chute or receptacle suitably arranged to receive it.

From the foregoing description and accompanying drawings it will now be readily understood that I have provided a novel method for rapidly and economically producing threaded tubular metal articles. As formed by my method these articles have a continuous solid helical thread which is very strong and rugged and of desired accuracy and uniformity. In accordance with my method the solid continuous thread is formed by a shearing and displacing of metal of the wall of the article radially thereof and a shaping or swaging of at least a portion of the displaced metal into the desired solid continuous helical thread.

It will also be understood from the foregoing description and accompanying drawings that I have provided novel apparatus for producing metal articles having a solid continuous helical thread, although the method of my invention may be carried out with this and various other apparatus and machinery.

While I have illustrated and described the method and apparatus of my invention in a somewhat detailed manner, it should be understood, however, that I do not wish to be limited to the precise steps of procedure and details of construction herein disclosed, but regard my invention as including such changes and modifications as do not involve a departure from the spirit of the invention and the scope of the appended claims.

Having thus described my invention, I claim:

1. The method of threading hollow metal articles which comprises displacing metal of the wall of the article only radially thereof by rolling a continuous groove in one side of the wall and thereby partially shearing the metal of the wall, and in the same operation swaging at least a portion of the displaced metal into a continuous solid thread on the other side of said wall.

2. The method of forming a solid continuous helical thread on a tubular metal article which comprises rolling a continuous groove in the article and thereby shearing and displacing metal of the wall of the article only radially thereof and in the same operation shaping the displaced metal into a solid continuous thread.

3. The method of threading tubular metal

articles which comprises applying pressure on one side of the wall of a tubular article and thereby forming a continuous groove in said one side and meanwhile supporting the metal of the wall from the reverse side thereof immediately adjacent the area being stressed whereby metal of the wall is sheared and displaced in a radial direction only, and in the same operation shaping at least a portion of the sheared metal into a solid continuous thread.

4. The method of threading hollow metal articles which comprises applying radially acting pressure to one side of the wall of an article at a plurality of areas lying substantially opposite consecutive convolutions of a helical groove of a die disposed on the reverse side of said wall and meanwhile supporting the wall on said die at each side of said areas whereby metal of the wall at said areas is sheared and displaced radially only of the article into the die groove and in the same operation is shaped into a continuous solid helical thread.

5. The method of forming a helical thread on the wall of a tubular article which comprises pressure rolling the wall of the article between cooperating rolls, one of which has a helical land of opposite hand to a helical land on the other roll with the convolutions of the land substantially opposing the convolutions of the helical groove of said other roll, and thereby causing the land of one roll to shear and displace metal from said wall radially only thereof into the helical groove of the other roll while the land of said other roll supports the wall at each side of and adjacent to the metal being displaced, and in the same operation swaging the displaced metal into a solid continuous substantially V-shaped helical thread.

6. The method of threading tubular metal articles which comprises applying pressure to opposite sides of the wall of a tubular blank by cooperating die members, one of which has a helical land with an intervening helical groove and the other of which has a helical land of the opposite hand with the convolutions thereof disposed substantially opposite the convolutions of said groove, and causing relative rotary movement between said other die member and the blank while said pressure is maintained and thereby shearing and displacing metal of the wall of the blank radially only thereof into said groove by a shearing action and in the same operation forming the displaced metal into a continuous solid helical thread and meanwhile supporting the metal of the wall by the helical land of said one die member at each side of the metal being displaced.

7. In apparatus of the character described the combination of inner and outer die members adapted to receive therebetween the wall of a hollow article to be threaded, one of said die members having a helical groove therein and an intervening helical land for supporting engagement with one side of said wall, and the other die member having a ridge disposed opposite said helical groove, means for causing relative rotary movement between said die members, and means for pressing said members toward each other, said land and ridge each having a contact face of substantial width whereby the ridge when pressed into the wall pushes metal thereahead

relative to metal adjacently supported by the land.

8. In apparatus of the character described the combination of inner and outer die members adapted to receive therebetween the wall of a hollow article to be threaded, one of said die members having a helical groove therein and an intervening helical land for supporting engagement with one side of said wall, and the other die member having a ridge disposed opposite said helical groove, said ridge having a contact face of substantial width for engagement with the other side of said wall, means for causing relative rotary movement between said die members, and means for pressing the die members toward each other, whereby the relatively wide contact face of the ridge partially shears the wall of the article and pushes metal thereof into said groove.

9. In apparatus of the character described the combination of cooperating inner and outer die rolls adapted to receive therebetween the wall of a hollow article to be threaded, one of said rolls having a helical groove therein and a helical land for supporting engagement with portions of one side of said wall, and the other roll having a helical land of opposite hand for engagement with the opposite side of said wall at points substantially opposite the convolutions of said groove, means for causing relative rotary movement between said rolls, and means for meanwhile pressing said rolls toward each other, said helical lands each having a contact face of substantial width.

10. In apparatus for threading relatively thick walled hollow metal articles the combination of inner and outer die members having cooperating continuous helical shear elements thereon, means for causing relative rotary traversing movement between said die members, and means for meanwhile pressing said die members toward each other whereby metal is sheared and displaced substantially radially of said wall to form a continuous solid thread thereon, said shear elements each having a substantially flat contact face of substantial width.

11. In apparatus for threading hollow metal articles the combination of a mandrel having thereon a helical ridge and an intervening helical groove, and a die roll adjacent the mandrel and having a ridge thereon disposed substantially opposite said helical groove for shearing cooperation with said helical ridge, the ridges of said die roll and mandrel having substantially flat contact faces of substantial width for engagement with opposite sides of the wall of the article.

12. In apparatus for threading hollow metal articles the combination of a support, a die mandrel, means for rotating said mandrel with an article thereon, a plurality of bearing members mounted on said support for transverse movement relative to the axis of rotation of said mandrel, spindles rotatably supported by said bearing members to extend in adjacent substantially parallel relation to said mandrel, die rolls on said spindles to be driven thereby, anti-friction members on each spindle at each side of the die roll thereon, and rotary cam means having an internal clearance recess for said die rolls and cam surfaces at each side of the clearance recess for cooperation with said anti-friction members.
